UNITED STATES PATENT OFFICE.

JAMES NEAL AND FRANK J. ZIRON, OF BRIDGEPORT, CONNECTICUT.

DESIGN FOR A PICTURE-FRAME.

SPECIFICATION forming part of Design No. 23,451, dated July 10, 1894.

Application filed June 6, 1894. Serial No. 613,708. Term of patent 3½ years.

To all whom it may concern:

Be it known that we, JAMES NEAL and FRANK J. ZIRON, citizens of the United States, and residents of Bridgeport, in the county of 5 Fairfield and State of Connecticut, have invented a certain new and original Design for Picture-Frames, of which the following is a specification.

This invention relates to a design for a picture frame and is particularly adapted for 10 photographs.

The leading feature of our design comprises a frame of rectangular shape having represented thereon a certain distinctive ornamentation as shown, and consisting of military 15 emblems together with an American eagle at the top and the American flag upon each side, all of which present an irregular inner and outer edge.

Upon the accompanying drawing, which forms a part of this specification, 1 represents 20 an eagle, and 2 a pair of swords, the blades of which cross each other and having the appearance of supporting said eagle.

25 3 represents bugles at each side of the swords and eagle and in practice serve to connect the eagle with the flags 4. These flags are displayed upon suitable staffs, the upper ends of which are provided with a spear, and have 30 dangling therefrom cords and tassels. Midway upon these flag staffs are represented

drums 5 partially encircled by wreaths 6. Below the drums and wreaths upon either side are military emblems, consisting of rifles 7 and muskets 8, together with knapsacks, caps and canteens, all of which have the appearance of leaning against and being supported by the staffs of the American flags. 35

The lower portion of the design, like the rest of it, is made up of military emblems, the principal one being a shield 9 bearing the stars and stripes and supported by a pair of cannons 10, and immediately below these are a number of cannon balls 11, also a strip of bunting entwined between the several articles just described. 40

In the employment of this design we may omit a few of the articles represented, particularly some of those at the bottom, yet in outline and character it would remain the same. 50

What we claim as our invention, and desire to secure by Letters Patent, is—

The design for a picture frame substantially as herein shown and described.

Signed at Bridgeport, in the county of Fair- 55 field and State of Connecticut, this 26th day of May, A. D. 1894.

JAMES NEAL.
FRANK J. ZIRON.
